(57) **CLAIM**

The ornamental design for a lid for a bottle, as shown and described.

DESCRIPTION

FIG. 1 is a perspective view of a lid for a bottle, according to the invention.

FIG. 2 is a front, elevation view of the lid for a bottle.

FIG. 3 is a rear, elevation view of the lid for a bottle.

FIG. 4 is a left side, elevation view of the lid for a bottle.

FIG. 5 is a right side, elevation view of the lid for a bottle.

FIG. 6 is a top, plan view of the lid for a bottle; and,

FIG. 7 is a bottom, plan view of the lid for a bottle.

The broken lines in the drawings illustrate portions of the lid for a bottle that form no part of the claimed design.
